UNITED STATES PATENT OFFICE.

HAMPTON J. POPE, OF BOLLING, ALABAMA.

BOLL-WEEVIL CATCHER.

1,408,030.

Specification of Letters Patent. Patented Feb. 28, 1922.

Application filed October 19, 1920. Serial No. 417,960.

To all whom it may concern:

Be it known that I, HAMPTON J. POPE, a citizen of the United States, residing at Bolling, in the county of Butler and State 5 of Alabama, have invented certain new and useful Improvements in Boll-Weevil Catchers, of which the following is a specification, reference being had therein to the accompanying drawings.

- 10 This invention relates to a boll weevil catcher, and has for its object the construction of a comparatively simple and efficient machine for the destruction of boll weevils found on cotton plants.
- 15 With this and other objects in view, my invention comprises certain novel combinations, constructions and arrangements of parts as will be hereinafter described, illustrated in the accompanying drawings, and 20 more particularly pointed out in the appended claims.

In the drawings:

Figure 1 is a view in side elevation of a machine constructed in accordance with the 25 present invention.

Figure 2 is a rear view of my machine.

Figure 3 is a top plan view of the machine.

Figure 4 is a section, taken on line 4—4, Fig. 2, and looking in the direction of the 30 arrows.

Figure 5 is a fragmentary, perspective view of the machine, showing particularly the paddle wheel supporting frame.

Figure 6 is a perspective view of the pan.

35 Figure 7 is a sectional view, taken on line 7—7, Fig. 6.

Figure 8 is a fragmentary, plan view of the lower end of the hood, prior to folding, while

40 Figure 9 is a fragmentary view of the hood, showing it on the bars of the paddle wheel supporting frame.

Referring to the drawings by numerals, 1 designates the beam to the rear end of 45 which are secured the handles 2. The driving wheel 3 is suitably attached to the beam, and fastened by means of shaft 4, to wheel 3, is a sprocket 5. Upon sprocket 5, is a sprocket chain 6, and this chain is passed 50 over sprocket 7, which sprocket 7 is fastened to shaft 8. To the inner end of shaft

8 is secured a beveled gear 9, and beveled gear 9 meshes with a beveled gear 10 on shaft 11. Fixedly secured to shaft 11 is a sprocket 12, upon which sprocket 12 is positioned a sprocket chain 13. The sprocket chain 13 is also positioned upon a sprocket 14, Fig. 2, which sprocket 14 is secured to shaft 15.

The fan or paddle wheel 16 includes shaft 60 15, discs 17, arms 18 and blades 19.

The paddle wheel 16 is carried by a supporting frame comprising pairs 20 of standards, each pair 20 including an inner standard 21 and an outer standard 22. Each 65 standard is twisted as at 23, near its lower end, and the lower end extends below the beam 1, Fig. 5. The upper ends of the standards are adjustably fastened to the horizontal bars 24. The upper ends of said standards are spread apart in substantially a V-shaped manner, giving greater rigidity to the frame, constituted by said standards and bars. In the apertures 25, near the outer 70 ends of the bars 25, is journaled the shaft 75 15. A brace 26 is attached, at 27, to one of the bars 24, and the other end of the brace is attached to the outside of one of the handles 2. A suitable tightening device 28 (Figs. 2 and 3) is attached to the brace 26, at 29, for pressing upon the sprocket chain 13 and keeping the chain from jumping or becoming displaced accidentally off its sprockets 12 and 14; this tightening device 80 is common in the art, and is of any 85 ordinary construction.

Beneath the fan or paddle wheel 16, I place a pan 30. This pan 30 includes a poison liquid-containing body 31 with a flat back 32 that is attached, by fastening means 90 extending through apertures 33 and slots 33^a in the depending, lower ends of the standards 21 and 22, directly under the paddle wheel. The forward end of the pan 30 is provided with a projection 34, which projection has a nose 35 and a comparatively long slanting side 36 for directing the plants positively against the outer side of the pan so that the paddle wheel can brush the boll weevil, potato bugs or insects into 100 the pan, and by reason of poison liquid being in the pan the insects will be killed.

The top of the projection 34 is closed by means of stopper or cap 37. The pan, including the projection, can easily be filled with poison fluid.

5 A pair of vertical, hood-supporting standards 38 are fastened near their lower ends by any ordinary means to the bars 24, and each upright 38 is provided near its upper end with a horizontal block 39. A sheet-
10 metal hood 40 is fastened to the blocks 39 by bolts 41 passing through the hood and the blocks (Fig. 2). The lower end of the hood 40 is slotted, at 42, for producing the horizontal lugs 43, resting upon the top of
15 the bars 24 (Fig. 9) and the vertical lugs 44, resting against the inner vertical faces of the bars 24. A rod 45 extends through the bars 24 and lugs 44, fastening the hood at its lower end against displacement off
20 the bars 24.

It is to be noted that the standards 21 and 22 are fastened together below the beam 1, at 21^a, so that when the standards are moved, all will be moved in a vertical plane
25 together. The pan 30 is also fastened to the lower depending ends of the standards 21 and 22 through the medium of suitable fastening means placed in the apertures 33 and the elongated slots 33^a of the standards.
30 Hence, when the standards are moved, the pan 30 and the paddle wheel will be moved simultaneously.

The object in thus arranging the machine is to enable the farmer to make arrangements for working cotton at any height he
35 finds necessary. It may be necessary to have the pan 30 close to the ground, or some distance above it. Of course, the relation between the paddle wheel to the pan must be
40 kept constant, therefore, the fastening of them together.

It is to be noted that slots 33^b in the upper ends of the standards 21 and 22, enable the bars 24 and the standards to be adjustably secured together, so that the paddle wheel can be raised away from the pan, or lowered slightly toward the same, at the will of the operator.

In operation the machine is pulled along
50 the row by a mule or horse, and the paddle wheel is caused to hit against the cotton plants, brushing the insects or boll weevils into pan 30 and, by reason of the pan containing poison fluid or poison powder, the
55 insects will be killed.

While I have described the preferred embodiment of my invention, and have illustrated the same in the accompanying drawings, certain minor changes or alterations
60 may appear to one skilled in the art to which this invention relates, during the extensive manufacture of the same and I, therefore, reserve the right to make such alterations or changes as shall fairly fall within the scope
65 of the appended claims.

What I claim is:

1. In a machine of the class described, the combination with a beam, of a frame supported upon said beam including pairs of standards, the standards in each pair being 70 secured at their lower ends close together and having their upper ends spread apart, horizontal bars fastened to the upper ends of said standards, a paddle wheel journaled upon the outer end of said bars, a pan secured upon the beam under said paddle wheel, and means connected to the frame and paddle wheel for rotating the same.

2. In a machine of the class described, the combination with a beam, of pairs of standards supported upon said beam, each pair of standards arranged in the form of a V, a bar attached to the upper ends of each pair of standards, a paddle wheel journaled upon said bars, handles secured to said beam, a 80 brace connected at one end to one of the bars and at the other end to one of said handles, a pan carried by the beam under said paddle wheel, and means for driving or rotating said paddle wheel.

3. In a machine of the class described, the combination with a beam, of a frame secured to said beam, said frame including bars, a paddle wheel journaled upon said bars, a hood-supporting standards attached 95 to said bars, a hood supported near one end upon said standards and supported at its other end upon said bars, a pan positioned under said paddle wheel and carried by the beam, and means for rotating the paddle 100 wheel.

4. In a machine of the class described, the combination with a beam, a frame supported upon said beam, of hood-supporting standards carried by said frame, blocks secured to the upper ends of said standards, a hood engaging said blocks and standards, pairs of bolts passing through the blocks and through the hood, a paddle wheel journaled upon said frame beneath said hood, a pan carried by the beam beneath said paddle wheel, and means for rotating said paddle wheel.

5. In a machine of the class described, the combination with a beam, of a frame supported upon said beam, said frame including a pair of bars, a hood supported at its outer end upon said bars, the inner end of said hood being slotted and bent producing a pair of horizontal lugs and a pair of vertical lugs, said horizontal lugs resting upon said bars, said vertical lugs resting against or contiguous to the inner faces of the bars, a rod extending through the bars and the vertical lugs securing the hood against displacement at its inner end off the bars, a paddle wheel journaled upon the bars beneath the hood, and means for rotating the paddle wheel.

6. In a machine of the class described, the 130

combination with a beam, of a frame carried by said beam, a hood having its inner end resting partly upon the frame and being secured between portions of said frame, up-
rights secured to said frame and supporting the outer end of said hood, a paddle wheel journaled upon said frame beneath said hood, a pan carried by the beam beneath

the paddle wheel, and means for rotating the paddle wheel. 10

In testimony whereof I hereunto affix my signature.

HAMPTON J. POPE.

Witness:

J. H. STEINER,
